[57] CLAIM

The design for a tamper evident, pull-push closure, as shown and described.

DESCRIPTION

FIG. 1 is an exploded perspective view with the cap shown removed and the tamper evident strip partially pulled away.

FIG. 2 is a perspective view with the cap shown attached.

FIG. 3 is a top plan view of FIG. 2.

FIG. 4 is a front elevation of FIG. 2.

FIG. 5 is a rear elevation view of FIG. 2.

FIG. 6 is a left side elevation view of FIG. 2; and,

FIG. 7 is a right side elevation view of FIG. 2.

The bottom and the interior of the closure is disclaimed.
